Filed Dec. 17, 1962, Ser. No. 245,158
10 Claims. (Cl. 220—110)

This invention relates to carriers and more particularly to an improved collapsible bottle carrier for handling a plurality of bottles or multiple units of bottle cartons. The bottle carrier embodied by the present invention is particularly adapted for handling, displaying and marketing multiple cartons of bottles or the like, and possesses characteristics particularly satisfying as regards strength, ease of storage, cost and attractiveness in a carrier intended to perform such functions.

The bottle carrier is characterized in that it comprises a lightweight, collapsible assembly including only a one piece folded paperboard body and wire rim means. The one piece folded paperboard body includes transverse parallel end and divider panels, and a bottom section joining the end and divider panels along carrier collapsing fold lines. The wire rim means is pivotally attached to each end and divider panel, and spans the panels in a parallel relationship with respect to the bottom section of the folded paperboard body, thereby maintaining the panels in fixed parallel relationship with respect to one another whether the carrier is erect or collapsed. A carrier handle formed integral with either end or divider panels serves also as a positive and direct carrier erecting means whereby force applied to the carrier handle to rotate the panel including the handle is transmitted directly to the rim means and in turn to all the other panels to which the rim is attached to cause similar rotation thereof.

Hitherto bottle carriers of the present collapsible type have been constructed and assembled from separate panel, bottom, end and handle sections, as for example in Glenny, U.S. Patent No. 2,551,262. Erection of this type of carrier is not possible by merely rotating the handle of the carrier and the present combination of structural elements provides this handle erecting function based upon the novel structural elements.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

FIGURE 1 is a perspective view of one erected form of carrier embodied by the present invention;

FIGURE 2 is a vertical sectional view taken along 2—2 of FIGURE 1;

FIGURE 3 is a plan view of the blank sheet used in forming the body of the carrier embodiment of FIGURE 1;

FIGURE 4 is a side elevational view of the carrier embodiment of FIGURE 1 in collapsed condition;

FIGURE 5 is a plan view of a blank sheet used to form the body of the carrier embodiment of FIGURE 6;

FIGURE 6 is a perspective view of another erected form of carrier embodied by the present invention;

FIGURE 7 is a perspective view of another erected form of carrier embodied by the present invention;

2

FIGURE 8 is a perspective view of another erected form of carrier embodied by the present invention;

FIGURE 9 is a perspective view of another form of carrier embodied by the present invention;

FIGURE 10 is a plan view of a blank sheet used to form the body of the carrier of FIGURE 9;

FIGURES 11 and 12 are perspective views of modified forms of the carriers of FIGURES 6 and 7; and

FIGURE 13 is a perspective view of the carrier of FIGURE 11 with a grid to provide cells.

In FIGURE 1 the material of the blank sheet 11 is shown in folded condition to form body 10 and in such configuration comprises transverse, parallel end panels 26, transverse divider panel 28 parallel to and disposed between the end panels 26, and bottom section 30, the bottom section 30 in this instance comprising blank panel sections 32, also shown in FIGURE 3. The fold lines 15 at the intersection of end panels 26 and panels 32 comprising bottom section 30, and the divider panel fold lines 18 at the intersection of divider panel 28 and panel bottom section 30 comprise carrier collapsing fold lines for enabling the erected carrier as shown in FIGURE 1 to be collapsed to the position shown in FIGURE 4 by allowing the end and divider panels 26 and 28 to be rotated relative to the bottom section 30 about said fold lines 15 and 18 respectively, in a manner to be more fully described below. It will be noted that the end and divider panels 26, 28 of body 10 comprise double layers of blank body material since they are formed by folding blank panel sections 26', 28' of sheet 11 back upon themselves along fold lines 14 and 19, respectively. The panel sections 26' and 28' forming the end and divider panels 26 and 28 are secured together by suitable means such as mechanical fasteners 34, by adhesive bonding (not shown), or some other suitable means. In bonding the panel sections or layers 26' comprising end panels 26 along fold lines 14, which, as can be seen from

FIGURES 1 and 2, form the free upper edge portions of end panels 26, apertures 36 are formed which extend transversely along the upper edges of panels 26. In securing the panel section 28' together by mechanical fasteners or other means, care must be taken that the apertures 36 are not closed by bonding the panel sections 26' completely together up to fold line 14. In securing together the panel sections or layers 28' comprising the divider panel 28, an aperture 38 is formed transversely of said divider panel by leaving an area of each panel section 28' unsecured to the other. The aperture 38, as will be apparent from FIGURE 2, lies in the same horizontal plane as apertures 36 in end panels 26 of the folded blank 10.

The divider panel 28 in the embodiment of FIGURES 1, 2, 3 and 4 includes a free upper area 40 which extends above the plane of the apertures 36, 38, and a handle aperture 41 extending through both blank layers of the divider panel 28 is formed in this area by the juxtaposition of apertures 22 provided on either side of fold line 19 of blank sheet 11, as seen in FIGURE 3. The apertures 36 and 38 in panels 26 and 28 comprise rim receiving apertures which receive certain portions of rim 12 in the manner to be described below.

As seen best in FIGURES 1 and 2, the carrier embodied by the present invention includes a wire rim means 12 which is adapted to reinforce the carrier structure, and maintain the end panels 26 and divider panel 28 in parallel relationship at all times, whether the carrier is erect or collapsed. This is accomplished by pivotally attaching the wire rim means 12, which in this embodiment is a continuous length of longitudinally rigid wire or rod, to the end and divider panels 26 and 28 in such a manner that the wire rim-to-panel joint at each end and divider

panel permits relative rotation between the rim and panel about a transverse axis parallel to the bottom panel 30, while non-rotational relative movement between each of the panels and rim is restrained. That is, the manner of attachment of the rim 12 with the folded end and divider panels 26 and 28 of the body 10 is such that each panel 26, 28 may be rotated with respect to the bottom panel 30 from its erect position as shown in FIGURE 1 to its collapsed position as shown in FIGURE 4 about its collapsing fold line, the collapsing fold line for panels 26 being fold lines 15, the collapsing fold line for divider panel 28 comprising fold lines 18, without mechanical interference with such rotation being caused by the rim member 12. At the same time, the rim 12, being attached to the erected end and divider panels 26, 28 at points lying in the same horizontal plane parallel to but spaced from the bottom panel 30 as seen clearly in FIGURE 2, maintains the end and divider panels in parallel relationship throughout their rotational displacement about their collapsing fold lines 15 and 18, respectively.

Considering in detail the structural relationship between the assembled rim 12 and body 10 of the carrier embodied by FIGURES 1, 2 and 4, such structure being essentially typical of all embodiments of the present invention illustrated by way of example, the rim 12 as seen in FIGURE 1 includes transverse portions 45 which extend transversely through the apertures 36 in end panels 26, and a transverse portion 46 which extends through aperture 38 provided in divider panel 28. Since the apertures 36 and 38 are disposed in the same horizontal plane when the carrier is in erect position as seen in FIGURE 2, the rim 12 forms a rigid interconnection between the folded end and divider panels 26, 28 in a plane horizontal to but spaced from the bottom panel 30. As stated above, the apertures 36 each are formed specifically in this instance to freely receive the rim portions 45, and, when so assembled, comprise pivotal rim-to-panel joints which allow pivotal motion between panels 26 and 28. At the same time, non-pivotal motion between the panels and rim in the plane of each of the panels is restrained by reason of interference between the rim portions 45, 46 and the body material layers 26', 28' comprising the panels 26 and 28, the fastening means 34 joining the body material layers 26', 28' and, in the case of the end panels 26, the folded over body material at fold lines 14. In referring to non-rotational motion between each of the panels and rim in the plane of each panel, it is, of course, to be understood that this refers to relative motion of the rim along the line of separation of the blank layers 26', 28' in a vertical direction as the carrier is viewed in FIGURE 2. Relative motion of the rim 12 in a transverse sense relative to the panels 26 and 28 is always prevented by reason of the configuration of the rim 12 as is clearly apparent from FIGURE 1, for example.

An important feature of the carrier of the present invention lies in the provision of a folded end or divider panel having a free portion or area extending above or beyond the rim-to-panel joint, that portion of the panel including an integral handle means. For example, as seen in FIGURE 1, the divider panel 28 includes a free upper area 40 which extends above the joint between the rim 12 and panel 28, the area 40 having a handle aperture 41 extending therethrough. The advantage of such a feature lies in the fact that the carrier of the invention may be readily grasped at the handle while in the collapsed position, as seen in FIGURE 4, for example, and erected instantly by simply rotating the panel that is grasped to an upright position. The rotation of the single panel to an erect position simultaneously causes erection of all panels attached to the rim by means of the rim interconnection between end and divider panels. While the panel is still grasped and thereby held in the erected position with one hand, the other hand is free to load the carrier, after which it may be transported by the same handle. Positive control of erection and collapsing of the carrier,

5 maintaining the carrier in erect position, and transporting of the carrier all may be readily accomplished by means of the handle provided in the folded end or divider panels of the carrier.

10 Accordingly, in the embodiment of FIGURES 1, 2 and 4, positive erection, collapsing and transportation of the carrier shown all may be accomplished by grasping divider panel 28 through aperture 41 in body 10 formed by apertures 22 in blank sheet 11 as shown in FIGURE 3, and exerting necessary rotational forces upon the panel 28.

15 In FIGURE 6 there is shown another carrier embodiment of the present invention. In this instance the one-piece carrier body 10 is formed from a blank sheet 11' cut and scored as shown in FIGURE 5. It will be readily apparent that in all essentials the blank sheet of FIGURE 5 is substantially the same as the blank of FIGURE 3 used in forming the carrier of the FIGURE 1 embodiment except that the blank 11' is cut and scored to allow its being folded so as to form end panels 26 with free upper areas 40' having handle apertures 41' therein in the same manner as the divider panel 28 of the FIGURE 1 carrier embodiment. In the carrier embodiment of FIGURE 6, the mechanical fasteners 34 securing the body material layers 26' comprising the end panels 26 restrain non-rotational relative motion between the end panels and rim means 12 in the plane of panels 26, while in the case of the divider panel 28, non-rotational relative motion between the divider panel 28 and rim 12 in the plane of panel 28 is restrained on one side by the body material folded over upon itself along fold line 19, and on the other side by the mechanical fasteners securing together the body material layers 28' comprising panel 28.

20 FIGURES 7 and 8 show still different embodiments of the present carrier incorporating features included in the carrier shown in FIGURES 1 and 6. It will be readily appreciated that any number of divider panels 28 may be formed from the one-piece body 10 comprising the carrier of the present invention, the only requirement being that the blank sheet used to form the body be of sufficient length to allow folded end and divider panels to be formed from the blank sheet. In each instance, of course, the divider panels 28 will comprise double layers of body material.

25 In FIGURE 7 the carrier shown includes two divider panels and a pair of end panels, all similar in construction to the single divider and double end panels, respectively, of the carrier shown in FIGURE 6. In FIGURE 8 the carrier shown includes three divider panels and a pair of end panels, the outer two divider panels and the end panels being similar in construction to the divider and end panels 26, 28 shown in FIGURE 1, the center divider panel being similar in construction to the divider panel 28 shown in FIGURE 6.

30 In FIGURES 9 and 10 there is respectively shown another form of carrier embodied by the present invention and the form of blank sheet used in constructing the carrier form illustrated. In the FIGURE 9 embodiment the body blank sheet 11 comprising the body 10 of the carrier is folded to provide end and divider panels 26 and 28 of double body material layers and furthermore, a bottom 47 comprising double layers of body blank material, the upper layer 30 being the full equivalent of the bottom section 30 as shown in FIGURE 1, the lower layer 30' comprising a center panel 48 of blank sheet 11 as shown in FIGURE 10.

35 FIGURES 11, 12 and 13 show modifications of the carriers illustrated in FIGURES 6 and 7. In each case the free upper areas 40', which extend above the joint between the rim 12 and panel 26, have been omitted and the handle apertures 41' have been placed in the panels 26. Such construction would require less stock for the blank and would be cheaper to make. FIGURE 13 shows how a grid of wire or similar material can be secured to the top of the carrier of FIGURE 11 to provide 24 cells

for bottles. In like manner any number of cells can be formed for these carriers.

Since certain changes may be made in the above product and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all the generic and specific features of the invention herein described, and all statements of the scope of the invention which, as a matter of language might be said to fall therebetween.

Having described my invention, what I claim as new and desire to secure by Letters Patent is:

1. A collapsible bottle carrier comprising a one-piece paperboard body including a pair of parallel folded end panels, at least one transverse folded divider panel between said end panels, said divider panel comprising double layers of body material secured together by suitable means, and a bottom section joining the end and divider panels along carrier collapsing fold lines; and wire rim means pivotally attached to and forming a rigid interconnection between said end and divider panels of said body in a plane parallel to but spaced apart from said bottom section, the wire rim-to-panel joints at each of said end and divider panels coacting to prevent substantial non-rotational relative movement between the said wire rim means and the end and divider panel structure in the plane of each of said end and divider panels, whereby the carrier may be erected or collapsed relative to the said bottom section by rotating the said end and divider panels about their collapsing fold lines, the same wire rim means maintaining the said end and divider panels of said body in parallel relationship.

2. The collapsible bottle carrier of claim 1, wherein said end panels comprise double layers of body material, and said wire rim means includes transverse portions extending between the body material layers comprising each of said end and divider panels to form each rim-to-panel attachment.

3. The collapsible bottle carrier of claim 1 wherein the double layers of body material comprising the divider panel are fastened together by a plurality of mechanical fasteners, and said rim means includes a transverse portion extending between the body material layers comprising the said divider panel, said portion being restrained from substantial non-rotational movement relative to said divider panel in at least one direction in the plane of said divider panel by means of said mechanical fasteners.

4. A collapsible bottle carrier comprising a one-piece paperboard body including a pair of transverse, parallel folded end panels, a folded divider panel parallel to and between said end panels, and a bottom section joining said end and divider panels along carrier collapsing fold lines, each of said end and divider panels comprising double layers of body material fastened together by suitable mechanical fastener means; and continuous wire rim means pivotally attached to and forming a rigid interconnection between said end and divider panels of said body in a plane parallel to but spaced apart from said bottom section, said rim means including transverse portions extending between the said body material layers comprising each of said end and divider panels to form each rim-to-panel attachment, said rim portions being restrained by suitable means from non-rotational movement relative to and in the plane of each of said end and divider panels, whereby the carrier may be erected or collapsed relative to the said bottom section by rotating the end and divider panels about their collapsing fold lines, the said wire rim means maintaining the said end and divider panels in parallel relationship.

5. The collapsible bottle carrier of claim 4 wherein the

said end panels each include an upper free edge portion comprising body material folded back upon itself, and a rim receiving aperture extending transversely between the body material layers comprising the said end panels adjacent said edge portion, the portion of said wire rim means passing between the body material layers comprising each end panel extending through said aperture in each of said end panels and being restrained against non-rotational movement relative to and in the plane of each of said end panels on one side by the said body material folded upon itself and on another side by the said mechanical fasteners joining together the body material layers comprising the said end panels, and the portion of said wire rim means passing between the said body material layers comprising the divider panel being restrained against lateral movement relative to and in the plane of said divider panels by the said mechanical fastener means joining the body material layers of said divider panel together.

6. The collapsible bottle carrier of claim 1 wherein the said end and divider panels comprise double layers of body material fastened together by the plurality of mechanical fasteners, and said rim means includes transverse portions passing between the body material layers comprising each of said end and divider panels to form each rim-to-panel attachment, each of said divider panels including an upper free edge portion comprising body material folded back upon itself, and a wire rim receiving aperture extending transversely between the body material layers comprising each of said divider panels, the portion of the said wire rim means passing between the body material layers comprising each of said divider panels extending through said aperture in each of said divider panels and being restrained against substantial non-rotational movement relative to and in the plane of each of said divider panels on one side by the said body material folded back upon itself, and on the other side by the said mechanical fastening means joining together the double body material layers comprising each of said divider panels, and the portion of said wire rim means passing between the body material layers comprising the said end panels being substantially restrained against non-rotational movement relative to and in the plane of each of said end panels by the said mechanical fastener means joining the body material layers of said end panels together.

7. The collapsible bottle carrier of claim 1 wherein a layer of body material underlies the said bottom section of said body.

8. The collapsible bottle carrier of claim 4, wherein said divider panel is provided with a hand holding aperture therein which extends above the point of attachment of said wire rim means to said divider panel.

9. The collapsible bottle carrier of claim 1 wherein said end panels each extend above the point of attachment of said wire rim means to each of said panels to form hand holding means.

10. The collapsible bottle carrier of claim 1 wherein three spaced parallel divider panels are included, each of the outermost two of said divider panels having a hand holding extension above the point of attachment of said wire rim means to each of said two divider panels.
